UNITED STATES PATENT OFFICE.

THEODORE D. PALMER, OF SYRACUSE, NEW YORK, ASSIGNOR TO T. D. PALMER COMPANY, OF SYRACUSE, NEW YORK, A CORPORATION.

SAD-IRON.

1,141,903.

Specification of Letters Patent.

Patented June 1, 1915.

Application filed November 17, 1911. Serial No. 660,859.

To all whom it may concern:

Be it known that I, THEODORE D. PALMER, of Syracuse, in the county of Onondaga, in the State of New York, have invented new 5 and useful Improvements in Sad-Irons, of which the following, taken in connection with the accompanying drawings, is a full, clear, and exact description.

This invention relates to certain improvements in sad irons for smoothing or polishing garments and fabrics by rubbing contact.

The primary object is to provide the sad iron with means for applying moisture to the surface of the garment just in advance 15 of the ironing surface so that the smoothing or polishing may follow immediately after the moistening.

Another object is to provide the sad iron with non-communicating compartments one 20 for delivering steam to the surface of the garment and the other for heating the iron.

Other objects and uses will be brought out in the following description:

In the drawings Figure 1 is a perspective 25 view of one form of my improved sad iron embodying the various features of my invention. Fig. 2 is a longitudinal vertical sectional view of the sad iron shown in Fig. 1. Fig. 3 is an inverted plan of the same sad iron. Fig. 4 is a longitudinal vertical 30 sectional view of a modified form of sad iron showing the perforated portion thereof in the same plane as the main body of the ironing surface. Fig. 5 is a transverse vertical sectional view taken on line 6—6, Fig. 4.

The sad iron in Figs. 1, 2 and 3 comprises a hollow cast metal body —1— of suitable size convenient for handling and preferably tapered toward its front end and is provided 40 with non-communicating compartments —2— and —3— separated by a partition —4—.

The greater portion of the bottom —5— of the sad iron is flat and smooth to form an ironing or polishing surface, while the front smaller portion —6— of the bottom is provided with a series of perforations —7— wholly in front of the imperforate ironing plate or bottom —5— and also wholly in 50 front of the heating chamber —3— which is substantially coextensive in area with the ironing plate —5—.

The front perforated portion —6— of the bottom of the chamber —2— is preferably 55 raised and surrounded by a marginal rib

—8—, the object in raising this surface being to permit the entrance of steam to the surface of the garment in advance of the ironing plate —5—, while the rib —8— serves the double purpose of smoothing out 60 the garment in advance of the ironing plate and also of confining the steam more or less within the perforated area by reason of its contact with the garment.

Moisture is preferably supplied to the 65 chamber —2— and through the perforations —7— to the surface of the garment by means of steam and for this purpose I have provided the sad iron with a steam pipe —9— adapted to be connected to any available 70 source of steam supply, said pipe leading to the interior of the chamber —2— by means of a branch pipe —10— having a self-closing valve —11— which is adapted to be opened by a hand lever —13— within 75 easy reaching distance of the handle as —14— by which the sad iron may be manipulated. That is, during the operation of ironing or polishing a garment, the operator may readily open the valve —11— by means 80 of the hand lever —13— by the same hand with which the handle —14— is gripped. This admission of the steam to the chamber —2— will, of course, heat the sad iron more 85 or less but insufficient to keep it at a uniform temperature and for this purpose I provide the sad iron with the extra heating chamber —3— which may be heated by any suitable heating means but preferably by a branch steam pipe —15— leading from the 90 main supply pipe —9— to the interior of the chamber —3— as best seen in Fig. 2. The front end of the ironing plate —5— is also tapered or somewhat pointed at —16— for the purpose of additionally smoothing 95 or spreading the garment out during the operation of ironing.

In Fig. 4 is shown a modified form of sad iron quite similar to that shown in Figs. 1 and 2 except that the perforated portion as 100 —26— of the bottom of the sad iron is disposed in substantially the same plane as the main body of the ironing plate for the purpose of supplying steam to the surface of the garment directly in advance of the ironing plate. Any water of condensation which may accumulate in the heating chambers 105 —3— or —21— may be drawn off through the branch pipe —15— by disconnecting said pipe from the source of steam supply 110

and depressing the open end thereof below the plane of the heating chamber, it being understood that the portion of the pipe —9— connected to the source of steam supply is flexible and may be readily connected or disconnected at will by any suitable form of coupling, not necessary to herein illustrate or describe.

What I claim is:

- 10 A sad iron having non-communicating compartments; one of said compartments having an imperforate bottom forming an ironing plate, the other of said compartments having a relatively smaller perforated bottom portion slightly raised above

and forward of the imperforate ironing plate; a flange around said perforated plate, the lower surface of the flange being in the same plane as the bottom of the imperforate ironing plate; means for supplying the compartment having the perforate bottom with moisture; and means for heating the other compartment, substantially as described.

In witness whereof I have hereunto set my hand on this 2nd day of November 1911. 25

THEODORE D. PALMER.
